(57) **CLAIM**

The ornamental design for an electronic shelf label holder, as shown and described.

DESCRIPTION

FIG. 1 is a top front perspective view of an electronic shelf label holder, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The article is shown with symbolic break lines in its length. The appearance of any portion of the article between the break lines forms no part of the claimed design.

1 Claim, 5 Drawing Sheets
